DESIGN FOR A CHANDELIER

Application filed May 4, 1929. Serial No. 31,097. Term of patent 3½ years.

To all whom it may concern:

Be it known that I, HARRY AGLOW, a subject of the King of Great Britain, and a resident of the city and county of Philadelphia, and Commonwealth of Pennsylvania, have invented a new, original, and ornamental Design for a Chandelier, of which the following is a specification, reference being had to the accompanying drawing, forming a part thereof.

The drawing shows a perspective view of the chandelier which comprises an ornament-

ed body A carrying a plurality of diffusing glass bowls B, and a central column C carrying arms D from which are suspended crystals E. These arms and crystals when illuminated by lamps in the bowls give the appearance of a fountain; which constitutes the dominant feature of the design.

I claim:

The ornamental design for a chandelier substantially as shown and described.

HARRY AGLOW.
